UNITED STATES PATENT OFFICE.

GEORGE J. BALKEY, OF GLENSHAW, PENNSYLVANIA.

THIMBLE.

1,394,394.

Specification of Letters Patent.

Patented Oct. 18, 1921.

Application filed July 25, 1919. Serial No. 313,194.

To all whom it may concern:

Be it known that I, GEORGE J. BALKEY, a citizen of the United States, residing at Glenshaw, county of Allegheny, State of 5 Pennsylvania, have invented certain new and useful Improvements in Thimbles, of which the following is a specification.

My invention relates to a new and improved sewing thimble, and more particularly to a thread-cutting thimble of the type shown and described in United States Letters Patent #1,260,952, granted to me on the 26th day of March, 1918.

The construction shown in the above-referred to patent includes a bead formed on the lower end of the body, a recess formed in the bead, and a cutting edge formed at one end of said recess. While the said construction is efficient, I find that the cost 10 of manufacture, especially of the less expensive thimbles, is considerably more than I anticipated; also, that it is of considerable advantage in thimbles of this class to have a double, or two cutting edges.

Among the objects of the present invention are, to provide a thimble of the class referred to that may be formed with or without a bead and at a single operation; a construction enabling the thread cutting element to be struck up from the body at a point spaced from the lower edge of the body, and at a single operation; and a construction embodying a plurality of cutting edges.

To these ends, the present invention consists of a sewing thimble formed with or without a bead at the open base of the body, and having a thread cutting element formed integral with the body, said cutting element being of such a character as to provide a 20 plurality of thread cutting edges.

In the accompanying drawings which illustrate applications of my invention,

Figures 1, 2 and 3 are elevational views 45 of a thimble embodying my invention showing the cutting element thereof of slightly different forms, as well as the lower edge of the thimble; and

Fig. 4 is a sectional view, the section being taken on line 4-4 of Fig. 1.

50 Referring to the drawings, 1 designates the hollow body of the usual or any suitable construction. The wall of said body surrounding the open base may be varied, as shown in the several forms illustrated.

55 Thus, in the form of Fig. 1, this portion 2

may be plain or it may be formed with a bead 2^a as shown by Fig. 2, or the bead may be omitted and the portion formed as indicated by 2^b in Fig. 3.

In all the forms of my invention shown, 60 the body is provided with a thread cutting element. This cutting element is preferably formed integral with the body and in the manufacture of the article it is struck up from the material constituting the body portion. The cutting element is disposed on the body at a point spaced away from the lower edge thereof, and extends substantially parallel with said edge. The element is designed to project slightly away from the surface of the body and to be substantially parallel therewith throughout its length, not sufficiently, however, to interfere in any manner with the use of the thimble, and the rear end of the element is raised out from 75 the body as well as the pointed end.

The cutting element of the form of Fig. 1 is designated by the numeral 3 and said element is provided with a rounded point *a* and two cutting edges *b* and *c*. In the form 80 of Fig. 2, the cutting element 3^a is provided with a rounded point and the two cutting edges. In this form, however, one of the cutting edges *a*² is formed with an indented portion 4. The cutting element 3^b of the 85 form of Fig. 3 has its respective cutting edges *a*³ and *b*³ terminating in slightly curved portions 5. Otherwise, this cutting element 3^b is similar to the cutting element of the form of Fig. 1.

By providing the two cutting edges, the thread may be readily cut in two places and the construction is of such a character that the thread may be cut very close to the material being sewed, or at any length desired 95 therefrom. The slightly projecting rounded point of the cutting element can be utilized for removing basting threads.

What I claim is:

1. A thimble comprising a hollow body 100 having a substantially V-shaped thread cutting member struck up from the body at a point spaced from the lower edge of the body and relatively near thereto and extending parallelly with the edge so that the edges of 105 said struck-up portion extend in a circumferential direction, said member being so struck out that it is substantially parallel with the outer surface of the body throughout its length.

2. A thimble comprising a substantially V-shaped thread cutting member struck up from the body portion at a point spaced from the lower edge of the body and relatively near thereto and extending parallelly with the edge, one edge of the cutting member having an indented portion therein, said member being so struck out that it is sub-

stantially parallel with the outer surface of the body throughout its length. 10

In testimony whereof I affix my signature in presence of two witnesses.

GEORGE J. BALKEY.

Witnesses:

J. M. GEOGHEGAN,
LOIS WINEMAN.
